US00D978662S

(12) **United States Design Patent** (10) Patent No.: **US D978,662 S**
Plasencia et al. (45) Date of Patent: **** Feb. 21, 2023**

(54) **SENSOR PACKAGE**

(71) Applicant: **Inficon, Inc.**, East Syracuse, NY (US)

(72) Inventors: **Joel Plasencia**, Liverpool, NY (US); **Russell Foster**, Kansas City, MO (US); **Dale Sass**, Grandview, MO (US); **John R. Hardesty, Jr.**, Climax Springs, MO (US); **Jennifer Reakes**, Hastings, NY (US)

(73) Assignee: **INFICON, Inc.**, East Syracuse, NY (US)

(**) Term: **15 Years**

(21) Appl. No.: **29/747,599**

(22) Filed: **Aug. 24, 2020**

(51) LOC (14) Cl. **09-03**

(52) U.S. Cl.

USPC **D9/418; D9/425**

(57) **CLAIM**

The ornamental design for a sensor package, as shown and described.

DESCRIPTION

FIG. 1 is a top perspective view of the sensor package shown with the cover and base applied according to our new design; FIG. 2 is a top perspective view of the cover of the sensor package shown removed for clarity of disclosure; FIG. 3 is a top perspective view of the base of the sensor package shown removed for clarity of disclosure; FIG. 4 is a top plan view of the sensor package of FIG. 1; FIG. 5 is a left side view thereof; FIG. 6 is a right side view thereof; FIG. 7 is a front facing view thereof; FIG. 8 is a rear facing view thereof; FIG. 9 is a top perspective view of the base of the sensor package shown in FIG. 3 in an environment of use; FIG. 10 is a bottom perspective view thereof; FIG. 11 is a top plan view of the base of the sensor package shown in FIG. 3; FIG. 12 is a left side view thereof; FIG. 13 is a right side view thereof; FIG. 14 is a front facing view thereof; FIG. 15 is a rear facing view thereof; FIG. 16 is a top plan view of the cover of the sensor package shown in FIG. 2; FIG. 17 is a left side view thereof; FIG. 18 is a right side view thereof; FIG. 19 is a front facing view thereof; FIG. 20 is a rear facing view thereof; FIG. 21 is a bottom plan view thereof; FIG. 22 is a bottom perspective view thereof; and, FIG. 23 is a bottom plan view of the sensor package shown in FIG. 1. Broken lines as shown are intended to show the environment of the design and do not form a part of the claimed design.

1 Claim, 7 Drawing Sheets
